UNITED STATES PATENT OFFICE.

CHARLES DEMPORTE, OF SOLVAY, NEW YORK.

METHOD OF COVERING EARTHENWARE COCKS WITH LEAD.

1,176,135.

Specification of Letters Patent. Patented Mar. 21, 1916.

Original application filed September 14, 1915, Serial No. 50,612. Divided and this application filed January 8, 1916. Serial No. 71,086.

To all whom it may concern:

Be it known that I, CHARLES DEMPORTE, a citizen of the United States, residing at Solvay, in the county of Onondaga and 5 State of New York, have invented certain new and useful Improvements in Methods of Covering Earthenware Cocks with Lead, of which the following is a specification.

My invention relates to earthenware cocks 10 employed in connection with the manufacture and handling of nitric, sulfuric, and other acids, and has for its object to provide an improved method of coating or covering such cocks, with lead, whereby the cocks are 15 suitably reinforced and protected, and may also be conveniently and readily connected to the lead pipes usually employed for conducting the acids to and from the cocks.

To the accomplishment of the foregoing 20 the invention consists primarily in adjustably disposing the earthenware cocks in suitable molds, and then pouring molten lead into the molds for casting leaden jackets or shells upon and around the whole cocks 25 at a single operation instead of applying sheet lead in a number of pieces to the cocks, as heretofore practised.

As one construction suitable for the purpose and found very efficient in use, reference is made to the accompanying drawing, 30 in which—

Figure 1 is a front-side elevation of the complete device ready for operation. Fig. 2 is an edge view of the same. Fig. 3 is a vertical longitudinal section taken on line 3—3 of Fig. 1. Fig. 4 is a top plan view. Fig. 5 is a view of the earthenware cock. Fig. 6 is a view of the cock after it is covered with lead. Figs. 7 and 8 are respectively an edge 40 and face view of the split cores.

In the drawing, 2 and 2' represent the halves or sections of a split-mold, which are preferably made of suitable metal, as cast iron, or steel, and having hollow sides, which 45 when the sections are placed together, as shown in the drawing, form the mold-cavity 3, in which is disposed an earthenware cock, as 4. Dowel-pins 5 carried by one section and entering sockets in the opposite section, 50 serve to prevent the lateral movement of the sections 2—2' when they are put together before each casting operation. The mold 2—2'

preferably stands up-right during the casting operations, and its lower end is supported by a block or part 6, which has a 55 suitable recess or cavity 7 in its top side to receive the lower ends of the mold sections, the said recess preferably being circular and large enough in diameter to allow the free insertion of the mold.

8 represents a platform, table, or base, having a raised portion, or base 9, the top of which is hollowed-out, as at 9' and is provided with an annular ledge 9'', upon which rests the block or plate 6. No other attaching means are provided for these parts, and the block 6 may be readily detached from the table 8, and the mold may also be detached from the block 6, for the purpose of removing the cock, after each casting operation.

Each earthenware cock 4 is hollow throughout longitudinally, and is also provided with a transverse tapering bore or opening 4', in which is disposed the usual 75 rotatable plug or valve 10, by means of which the flow of liquid or acid to and from the cock is controlled. The plug 10, has a handle 10', and may be held in the body 4 by any suitable means. When the cock 4 is 80 placed in a mold 2—2', it is supported therein by a core or plug 11, having a reduced portion 11' which is inserted in the lower open end of the body 4. The part 11 passes through a central perforation in the block 6, 85 and its lower end rests upon the upper end of a screw 12, which is threaded centrally through the table 8 and the raised portion 9. The said screw having a hand-wheel 12' for manipulating said part. By this construction and arrangement of the bottom support for the cock, the turning of the screw in opposite directions adjusts the cock vertically for bringing the transverse opening 4' concentric to similar, but slightly larger, 95 openings 13 and 14 which are formed in the opposite sides of the split mold, so that one half of each of said openings occurs in each of the sections 2 and 2' (see Figs. 1, 2 and 3). The reduced portion 11' prevents the molten 100 lead from entering the bottom end of the cock. Before the cock is disposed in the mold to receive its lead coating, the valve plug 10 is removed. The cock is then heated

sufficiently to prevent cracking due to the variance in the temperature of the molten lead in the cock. The cock is then disposed in the mold and adjusted relatively to the 5 sides and ends of the mold, and then the cock is filled with sand 15, to prevent the molten lead from flowing into the interior of the earthen body.

After the cock is set in position within 10 the mold split cores or parts 13' and 14' are inserted in the openings 13 and 14, and their inner ends are held against the corresponding faces of the body 4, and concentrically to the transverse opening 4', by a bolt 16, 15 the said cores being perforated at 16" for the purpose. The said bolt has a tapering head 16' which enters the counter-sunk outer face of the core 13'. The opposite or threaded end of the bolt 16 receives a nut 17 having a coneshaped portion which enters a corresponding socket in the face of the core 14'. The tightening up of the nut 17, draws the cores 13' and 14' tightly against the opposite faces of the body of the cock 4, and as 20 the said cores are larger in diameter than the opening 4', they not only prevent the lead from entering the said opening, but also prevent the lead from approaching close enough to the opening to touch, and thereby prevent the plug 10 of the cock 30 from properly seating in hole 4'. The tapered head of the bolt and the tapered nut tend to slightly expand the cores 13' and 14', so as to hold them tightly and firmly in place, and hold the earthenware cock from shifting in the mold, as well as prevent the escape of any of the lead at the said points. Before the bolt 16 is tightened-up a second 35 plug or core 18, having a reduced lower end 18', is inserted in the open top-end of the body 4, to prevent the molten lead from entering the upper end of the cock, as well as for coring the extended portion 19' of the lead jacket 19. The core 18 is held in place 40 by gravity. By referring to Fig. 3, it will be seen that the cores 11 and 18 are smaller 45 in diameter than the openings in the top and bottom ends of the mold 2-2'. This provision is made so that the molten lead 50 when poured in the mold will extend to the ends of the mold, and in doing so projects a short distance beyond the ends of the earthenware cock. This provides suitable lead extensions 19' and 19" to which the lead conducting pipes (not shown) may be attached 55 without interference from the earthenware. The lead piping referred to is usually secured to the terminals 19' and 19" of the cast covering or jacket 19, by a process which 60 is known as "burning." After the cock is disposed in the mold, one of the operators places the jaws of a pair of tongs against the opposite sides of the mold 2-2', at about 65 the positions or points indicated by the arrows 20 in Fig. 1, and he applies enough

pressure to the tongs to hold the mold steady, and at the same time prevent the sections 2-2' from spreading apart, while another operator pours the molten lead from a ladle 21 into the top opening 22, 70 which encircles the upper core 18, as indicated in Fig. 3. The dotted lines in Fig. 1, show the manner in which the mold sections 2 and 2' may be separated for inserting and removing the earthenware cocks. 75

My method for casting a lead jacket or covering upon earthenware cocks is extremely simple, and the cocks can be covered more rapidly and at about one fourth the expense, as compared with the old or prevailing method of doing such work, and the said work may be performed without any waste or loss from breakage of the fragile cocks. After the earthenware cocks are covered, by my improved method as herein 85 shown and described, they stand considerable rough handling and last a long time, which effects still a further saving. When the cocks have served their usefulness, the lead is reclaimed and re-molded, and may be 90 used for any suitable purpose without appreciable waste.

I have illustrated one form of apparatus embodying my invention and have described with some particularity the details of various 95 parts, but the casting apparatus is not confined to such details of parts as they may be varied without departing from my method claimed herein.

This case is filed as a division of my application filed September 14, 1915, Serial No. 50,612 in which the apparatus is claimed.

Having thus described my invention, what I claim as new and desire to secure by Letters Patent is—

1. The process of covering earthenware cocks with lead, which consists of placing a cock in a split mold and adjustably securing said cock in the said mold, then filling the hollow interior of the cock with sand, then plugging the open ends of the cock, and finally pouring molten lead into the hollow space between the mold and the said cock. 105

2. The herein described process of covering earthenware cocks with lead, which consists of disposing the earthenware cock concentrically in a suitable mold having a hollow interior larger than the said cock, then filling the cock with sand, then adjusting the said cock relatively to the inner walls of said mold, and finally pouring molten lead into the hollow space surrounding said cock. 115

3. The process of covering earthenware cocks with lead, which consists of heating the cocks, then disposing the cocks in a split mold, then filling the cocks with sand, then adjusting the cocks relatively to the inner walls of the mold, and finally pouring the molten metal into the mold for covering the cocks. 125

4. The process of covering cocks with metal, which consists of heating the cock, then placing the cock between the sections of a split mold having a hollow interior
5 larger than the said cock, then filling the cock with sand, then adjusting the cock relatively to the sides of the mold, then closing the top end of the cock and partially closing the top end of the mold, and finally filling the space surrounding the cock with 10 molten metal.

In testimony whereof I affix my signature.

CHARLES DEMPORT.
